Primary Examiner—Janice E. Seeger*Attorney, Agent, or Firm*—Norman B. Rainer[57] **CLAIM**

The ornamental design for a furniture leg protector, as shown and described.

DESCRIPTION

FIG. 1 is a front perspective view of the furniture leg protector showing my new design;

FIG. 2 is a perspective view thereof shown in an untied state;

FIG. 3 is a top view thereof; and,

FIG. 4 is a vertical sectional view.

The broken lines are for environmental purposes only and form no part of the claimed design. The bottom of the article is plain and unornamented.

FIG. 1

FIG. 3

FIG. 2

FIG. 4
